PUMP

John H. Collamore, Jr., West Barrington, R.I., assignor to Dart Union Company, a corporation of Rhode Island

Filed Oct. 17, 1967, Ser. No. 9,029

Term of patent 14 years

(Cl. D23—14)

FIG. 1

FIG. 2

FIG. 3

FIG. 5

FIG. 1 is a side elevational view of a pump showing my new design;

FIG. 2 is an end view thereof taken from the left hand side of FIG. 1;

FIG. 3 is an end view thereof taken from the right-hand side of FIG. 1;

FIG. 4 is a top view thereof; and

FIG. 5 is a bottom view thereof.

The undisclosed side is substantially the same in appearance as the side disclosed in FIG. 1.

I claim:

The ornamental design for a pump, substantially as shown and described.
